Des. 236,554
Patented Aug. 26, 1975

236,554

SHIPPING CONTAINER FOR X-RAY FILM OR SIMILAR ARTICLE

Woodrow W. Sands, 1810 38th St.,
Des Moines, Iowa 50310

Filed Dec. 26, 1973, Ser. No. 428,114

Term of patent 14 years

Int. Cl. D3—02

U.S. Cl. D87—1 R

FIG. 1

FIG. 2

FIG. 3

FIG. 4

FIG. 5

FIG. 6

FIG. 1 is a frontal perspective view of a shipping container for X-ray film showing my new design;

FIG. 2 is a frontal elevational view thereof;

FIG. 3 is a rear elevational view thereof;

FIG. 4 is a typical end view thereof as seen from the left-hand side of FIG. 3;

FIG. 5 is a top plan view thereof; and

FIG. 6 is a bottom plan view thereof.

I claim:

The ornamental design for a shipping container for X-ray film or similar article, substantially as shown and described.
